UNITED STATES PATENT OFFICE.

EUGENE C. AMSDEN, OF BOSTON, MASSACHUSETTS, ASSIGNOR TO CHARLES C. KENNEY,
OF WESTON, MASSACHUSETTS.

DESK HINGE.

Application filed May 28, 1925. Serial No. 33,449.

To all whom it may concern:

Be it known that I, EUGENE C. AMSDEN, a citizen of the United States, residing at Boston, in the county of Suffolk and State of Massachusetts, have invented certain new and useful Improvements in Desk Hinges, of which the following is a specification.

The invention to be hereinafter described relates to hinges for connecting the cover to the body of a desk and for other uses.

In the school room the pupils are liable to swing their desk covers open to their limits and allow them to drop and close with objectionable noise.

One of the purposes of the present invention, therefore, is to provide a desk hinge which has simple and efficient means for yieldingly resisting the swinging of the desk cover, thereby to prevent slamming of the same to its open and closed positions.

The character of the invention may be best understood by reference to the following description of one good form thereof shown in the accompanying drawing, wherein:

Fig. 1 is a side elevation of a portion of a desk provided with a hinge embodying the invention, a portion of the side of the desk being broken away to disclose the hinge;

Fig. 2 is a view similar to Fig. 1, showing the relation of the members of the hinge when the desk cover is open;

Fig. 3 is a perspective view of the hinge; Fig. 4 is a sectional detail taken on line 4-4 of Fig. 2; and

Fig. 5 is a perspective view of portions of the hinge members, the spring and the bolt, said parts being shown separated to disclose the form thereof.

Referring to the drawings, 1 designates a portion of the body of a desk provided with a top board 3 and a cover 5 which is connected to the body of the desk by a pair of hinges embodying the invention, but since these hinges are similar in construction, it will suffice to show and describe merely one of them.

This hinge comprises a member or plate 7 of general segmental form having a flange 9 projecting transversely from the plate and provided with a pair of holes 11 adapted

to receive screws 13 for securing said plate to the under face of the top board of the desk. Projecting from the plate 7 is a tongue 15 provided with a pair of holes 17 adapted to receive screws 19 for securing the tongue to the inner face of one of the sides of the body of the desk. Lugs 19, 21 and 23 project transversely from the plate at edges thereof in a direction opposite to the flange 9 for spacing the plate from the side of the body of the desk for a purpose to be described. To assist in the secure retention of the plate 7 to the body of the desk, the end of the tongue 15 may have a prong 25 projecting therefrom, and the lug 23 may have a prong 27 projecting therefrom. When the plate 7 is applied to the side of the desk, the prongs 25 and 27 will be forced therein, as will be readily understood.

A plate 29 of general segmental form, has a flange 31 projecting transversely therefrom and provided with holes 33 adapted to receive screws 35 for securing the flange to the under face of the desk cover. The plate 29 has a projection 37 which overlaps a projection 39 on the plate 7, said projections being provided with registering holes through which is entered a hinge rivet 41. The projections 37 and 39 on the plates may occupy a kerf in the top board of the desk. To limit the opening movement of the cover, the plate 29 may be provided with a hook 43 for engagement with the lug 23 referred to.

Next will be described the means for establishing friction to resist pivotal movement of the cover plate 29 relatively to the body plate 7. This means, in the present instance of the invention, comprises an arcuate slot 45 in the plate 29 and concentric with the hinge rivet 41. The plate 7 has a hole 47 therein registering with the arcuate slot. A leaf spring 49 is interposed between the plates, and has a hole 51 for registration with the slot 45 and the hole 47. A bolt 55 or equivalent element is entered through the arcuate slot, the spring hole 51 and the hole 47, the construction being such that when the nut 57 is tightened, it will press the plates toward each other and tension the spring, thereby to establish friction to resist pivotal movement of the cover plate rela-

- tively to the body plate. The spring may have a lip 59 for engagement with an edge 61 of the body plate, thereby to prevent the spring from turning on the shank of the bolt.
- 5 To prevent the nut 57 from working loose, the shank of the bolt may have flat faces 63 for engagement with flat faces of the hole 47. The bolt may be provided with a washer 65 interposed between the head of the bolt 10 and the cover of the plate. The cover plate may be bent along the line 67, so that the portion receiving the arcuate slot is offset somewhat from the projection 37, thereby to provide a space between the plates for receiving the spring.

The construction is such that when the cover is swung to open and closed positions, the arcuate slot will slide along the shank of the bolt, and the spring which is tensioned as described, will press against the cover plate and establish friction which opposes the rocking movement of the plate about the pivot rivet 41. The spring when it assumes its natural form is slightly bent 25 or curved, as will be noted in Fig. 5, but when the bolt is tightened, it is flattened somewhat. The bolt may be adjusted and tightened to vary the tension of the spring to provide more or less friction as desired.

30 The friction may be sufficient to hold the cover in any position of adjustment between its open and closed positions, and the friction may be such that it will prevent any possibility of the cover slamming to open 35 and closed positions.

The lugs 19, 21 and 23 referred to, prevent the cover plate from wiping against the inner face of the side of the desk, and provide a space between the body plate and the side 40 of the desk for receiving the bolt head and washer.

Preferably the arcuate slot 45 in the cover plate is of such length that one of the ends thereof will not engage the bolt and limit 45 the opening movement of the cover.

The movable plate 29 of the hinge is protected by the fixed plate so that the former is not liable to come into injurious contact with articles within the desk. Also, since 50 the spring is interposed between the plates of the hinge, it is covered and protected thereby. The nut of the bolt is readily accessible from the inside of the body of the desk for the purpose of varying the tension 55 of the spring as desired.

By my invention there is provided a hinge which has simple and efficient means for providing friction yielding to resist pivotal movement of one of the hinge plates 60 relatively to the other. The plates may be stamped out of sheet metal, and the parts of the hinge may be quickly and easily assembled.

It will be understood that the invention is 65 not limited to the specific embodiment

shown, and that various deviations may be made therefrom without departing from the spirit and scope of the appended claims.

What is claimed is:

1. A desk hinge comprising, in combination, a pair of pivotally connected plates having provision for connection with parts to be hinged together, one of said plates having an arcuate slot therein, and the other of said plates having a hole therein, a leaf 75 spring interposed between said plates and having a hole therein, and a bolt entered through said slot and holes for pressing the plates toward each other and tensioning the spring, thereby to establish friction to resist pivotal movement of one of said members 80 relatively to the other member.

2. A combination hinge and friction device comprising, in combination, a pair of plates having provision for connection with parts to be hinged together, said plates having portions pivotally connected, one of said plates having an arcuate slot therein and the other of said plates having a hole therein 85 registering with said slot, spring means interposed between said plates, and an element entered through said slot and hole and acting on said plates to hold the spring means in tension thereby to establish friction yielding 90 to resist swinging of one of said plates about their point of pivotal connection.

3. A desk hinge comprising, in combination, a pair of pivotally connected members having provision for connection with parts to be hinged together, one of said members 100 having an arcuate slot concentric with the point of pivotal connection of said members, and the other of said members having a hole therein registering with said slot, a spring interposed between said plates and having a hole therein, a bolt entered through said slot and holes for pressing the members toward each other to tension the spring, thereby to establish frictional resistance to pivotal movement of one of said members 105 relatively to the other member, one of said members having lugs projecting therefrom to prevent the other member and the bolt from engaging the surface of the part to which the member having the lugs is secured.

4. A desk hinge comprising, in combination, a pair of pivotally connected plates having provision for connecting them with parts to be hinged together, one of said members having an arcuate slot therein, and the other of said members having a hole therein, a leaf spring interposed between said members and having a hole therein, and a bolt entered through said slot and holes 110 for tensioning the spring to cause the same to press against the members, said leaf spring having a lip engaging an edge of one of the members to prevent the spring from 115 turning on the bolt.

5. A desk hinge comprising, in combination, a pair of pivotally connected members having provision for connecting them with parts to be hinged together, one of said members having an arcuate slot therein and the other of said members having a hole therein, a leaf spring interposed between said members and having a hole therein, and a bolt entered through said slot and 10 holes for pressing the plates toward each other to tension the spring, thereby to establish friction to resist pivotal movement of one of said members relatively to the other member, said bolt and the hole in the member having flat faces to prevent the bolt from turning to loosen its nut.
- 15 6. A desk hinge comprising, in combination, a pair of pivotally connected plates having provision for connecting them with parts to be hinged together, one of said plates having an arcuate slot therein and the other of said plates having a hole therein, a leaf spring interposed between said plates and having a hole therein, and a bolt entered through said slot and holes for 20 pressing the plates toward each other to cause the spring to press against one of the plates, thereby to establish friction to resist pivotal movement of said plate relatively to the other plate, one of said plates being bent to present an offset portion providing a space between the plates for receiving the leaf spring.

EUGENE C. AMSDEN.
